(57) **CLAIM**

We claim the ornamental design of a headset with speakers shaped as animal ears, substantially as shown and described.

DESCRIPTION

FIG. 1 is a front perspective view of a headset with speakers shaped as animal ears in accordance with the present invention;

FIG. 2 is a rear perspective view of the headset with speakers shaped as animal ears in FIG. 1;

FIG. 3 is a front view thereof;

FIG. 4 is a rear view thereof;

FIG. 5 is a top view thereof;

FIG. 6 is a plan view thereof;

FIG. 7 is a left side view thereof; and,

FIG. 8 is a right side view thereof.

The broken lines immediately adjacent the shaded areas represent the bounds of the claimed design while all other broken lines form no part of the claimed design.
